UNITED STATES PATENT OFFICE

164,489

DOLL

Annies Baxley Hahn, Savannah, Ga.

Application October 26, 1949, Serial No. 5,721

Term of patent 14 years

(Cl. D34—4)

To all whom it may concern:

Be it known that I, Annies B. Hahn, a citizen of the United States of America, residing at Savannah, county of Chatham, and State of Georgia, have invented a new, original, and ornamental Design for a Doll, of which the following is a specification, reference being had to the accompanying drawing, forming a part thereof wherein:

I claim:

The ornamental design for a doll, as shown.

ANNIES BAXLEY HAHN.
